RAILWAY CAR DOOR FIXTURE

Arthur E. Small, Michigan City, Ind., assignor to
Railway Metal Products Company, Chicago,
Ill., a corporation of Delaware

Application May 26, 1933. Serial No. 673,014

8 Claims. (Cl. 16—99)

The invention relates to railway freight cars and more particularly to side doors for such cars.

Side doors of railway freight cars are generally arranged to slide horizontally to open or close the door opening and anti-friction rollers are provided between the door and the supporting element to reduce the effort required to move the door. The inertia of such a door caused by the sudden

10 stopping or starting of the car bangs or slams it against the front or back stop causing damage to the car and the door and resulting in a leaky car. Even if the door is locked such inertia causes considerable strain upon the locking mechanism.

15 An object of my invention is to transfer the weight of the door from the anti-friction rollers to rigid supports so that the tendency of the door to move longitudinally of the track will be resisted by the friction between such rigid part of the door and the supports, thereby retaining 20 the door in a predetermined position. It is desirable to retain the door in a closed position or in full open position. However, my arrangement can be varied to retain the door in any position therebetween. The increased weight of the doors 25 caused by the metallic reinforcements used thereon and the use of all steel doors has increased the necessity for such an arrangement.

Another object of the invention is to provide a construction wherein the inertia of the door, due 30 to the movement of the car, is transferred from the locking or holding mechanism to supports rigidly attached to the car.

Another object of the invention is to provide a track having a smooth tread for engagement with 35 the door supporting rollers by positioning the means for raising the door off the rollers out of the path of engagement of such rollers with the tread.

Another object is to provide a relatively large 40 area of frictional contact between the door and the rigid support mounted on the car to resist the inertia tendency of the door to move longitudinally of the car (which reduces the wear of the engaging surfaces) and at the same time providing means to engage the door with the anti-friction rollers without dragging the door over 45 the length of the frictional contact area.

In the drawings:

50 Figs. 1, 2 and 3 show a typical railway car door provided with my improved door fixtures with the door in different positions.

Figs. 4, 5 and 6 are enlargements showing the relative position of the fixtures when the door is in different positions.

55 Figs. 7, 8 and 9 are cross sections of the door and car with the door in different positions.

Fig. 10 shows a modified construction.

In the form of my invention illustrated a 60 plurality of brackets 1, 2, 3, 4, 5 and 6 mounted upon the car are provided with a plurality of

rollers 7, 8, 9 and 10 normally supporting a horizontally movable door and members 15 and 16 are secured to the door so as to move therewith without interference with the primary supporting rollers. Rigid supports 17, 18 and 19 are 65 fixed to the car. Certain of the brackets are provided with secondary rollers 11, 12, 13 and 14 which are preferably concentric with the primary rollers and also preferably integral therewith.

The secondary rollers 11, 12, 13 and 14 are 70 located in close proximity to the members 15—16 when the members are resting upon the supports 17, 18 or 19 and the upper surfaces 20 of the secondary rollers are a little higher than the engaging surfaces 21 between the supports 75 and the members so that upon a slight movement of the door the members 15—16 engage and are slightly elevated by the secondary rollers and simultaneously the members are elevated out of contact with the supports, thereby 80 breaking their frictional engagement. The door then freely moves upon the secondary rollers for the length of the members whereupon the door drops into engagement with the primary rollers.

When the door is resting upon the primary 85 rollers, and the reverse movement takes place, the members engage and are raised by the secondary rollers. The door then freely moves upon the secondary rollers for the length of the members whereupon the door drops into (frictional) engagement with the supports. However, the door does not drop sufficiently for the door 90 to engage the primary rollers.

When the door is resting upon the primary 95 rollers 7, 8, 9 and 10 it may be freely moved back and forth from open to closed position or vice versa with very little effort but when the door is resting upon the supports 17, 18, 19 there is frictional contact between the door and the support which resists the tendency of the door to 100 move longitudinally of the car due to the shocks caused by the sudden stopping or starting of the car.

Fig. 1 shows the door in closed position with the members 15—16 resting upon the rigid supports 17—18. Fig. 4 is an enlargement showing the relation of the support 18, the member 16 on the door, the primary (9) and secondary (13) rollers. Fig. 9 is a section on line 9—9 of Fig. 4.

Fig. 2 shows the door initially opened wherein the members 15—16 have moved into engagement with the secondary rollers 11—13 and out of engagement with the supports 17—18. Fig. 5 is an enlargement showing the relation of the support 18, the member 16 and the primary (9) and secondary (13) rollers when the door is in this position. Fig. 8 is a section on line 8—8 of Fig. 5.

Fig. 3 shows the door in engagement with the primary rollers 8, 9 and 10; i. e., in a position 120

to be moved from open to closed position, without much exertion. The members 15—16 are out of engagement with the secondary rollers and as there is no secondary roller in the intermediate brackets (2—5) the door will roll freely upon the primary rollers until the members 15 and 16 engage the secondary rollers 12—14. In full open position the members 15 and 16 will rest upon the supports 18 and 19. Fig. 6 is an 10 enlargement showing the relation of the member 16, support 18 and primary (9) and secondary (13) rollers. Fig. 7 is a section on line 7—7 of Fig. 6.

In Figs. 7, 8 and 9 the usual parts of the car 15 are shown, such as side sill 24; floor 25; floor support 26 and threshold plate 27.

If the door is very large and heavy some manual means of initially opening or closing the door may be necessary, and for this purpose I have 20 shown the lever 30 pivotally (31) attached to the door which engages one side of the pintle 32 to initially open the door and the other side to close the door. A similar pintle (33) may be used upon bracket 5. However, any power mechanism 25 may be used as far as this invention is concerned.

Fig. 10 shows a modified construction wherein the elements of the invention are rearranged by providing two members 40—41 adjacent the rear 30 edge of the door and eliminating one bracket (4 in Fig. 1) on the car body. Various arrangements of the members on the door and the brackets on the car are possible under my invention. In this arrangement when the member 40 is moved to the right in Fig. 10 it rides over the adjacent roller and then comes into frictional contact with the bracket 18 and thus retains the door in a partially open position for ventilating the car. Such ventilation is desirable and even essential in certain seasons when some vegetables and fruits are being hauled in the car.

The accompanying drawings illustrate the preferred form of the invention, though it is to be 45 understood that the invention is not limited to the exact details of construction shown and described, as it is obvious that various modifications thereof, within the scope of the claims, will occur to persons skilled in the art.

50 I claim:

1. In a railway car, a plurality of brackets mounted upon the car, each provided with a roller normally supporting a horizontally movable door, members secured to the door out of the path of engagement of the rollers with the door, secondary rollers mounted in certain of said brackets positioned to be engaged by said members upon movement of the door to a predetermined position so as to raise said door out of engagement with the rollers, and supports positioned so that upon further movement of the door the members engage said supports so as to support the door independently of the aforesaid rollers whereby movement of the door is frictionally resisted.

2. In a railway car, a plurality of brackets mounted upon the car, each provided with a roller normally supporting a horizontally movable door, members secured to the door out of the path of engagement of the rollers with the door, secondary rollers integral with certain of said rollers positioned to be engaged by said members upon movement of the door to a predetermined position so as to raise said door out of engagement with the rollers, and supports

positioned so that upon further movement of the door the members engage said supports so as to support the door independently of the aforesaid rollers whereby movement of the door is frictionally resisted.

3. In a railway car, a plurality of brackets mounted upon the car, each provided with a roller normally supporting a horizontally movable door, members secured to the door out of the path of engagement of the rollers with the door, secondary rollers mounted in certain of said brackets positioned to be engaged by said members upon movement of the door to a predetermined position so as to raise said door out of engagement with the rollers, and supports positioned so that upon further movement of the door the members drop into engagement with the supports so as to support the door independently of the aforesaid rollers whereby movement of the door is frictionally resisted.

4. In a railway car, a plurality of brackets mounted upon the car, each provided with a roller normally supporting a horizontally movable door, members secured to the door out of the path of engagement of the rollers with the door, secondary rollers mounted in certain of said brackets positioned to be engaged by said members upon movement of the door to a predetermined position so as to raise said door out of engagement with the rollers, and supports positioned so that upon further movement of the door the members engage said supports so as to support the door independently of the aforesaid rollers whereby movement of the door is frictionally resisted.

5. In a railway car, a plurality of brackets mounted upon the car, each provided with a roller normally supporting a horizontally movable door, means to raise the door out of engagement with the rollers, and other means to support the door independently of the rollers and independently of the first mentioned means upon further movement of the door.

6. In a railway car, a plurality of brackets mounted upon the car, each provided with a primary roller normally supporting a horizontally movable door, some of said brackets each provided with a secondary roller, a member secured to the door, and a support mounted upon the car, said elements associated and arranged so that upon initial movement of the door said member engages one of the secondary rollers and raises the door out of engagement with the primary rollers and so that upon further movement of the door, said member moves out of engagement with the secondary roller and drops into engagement with the support whereby the door is supported by the support independently of any of said rollers.

7. In a railway car, a plurality of brackets mounted upon the car, each provided with a roller normally supporting a horizontally movable door, members secured to the door out of the path of engagement of the rollers with the door, parts mounted on the car positioned to be engaged by said members upon movement of the door to a predetermined position so as to raise said door out of engagement with the rollers, and supports positioned so that upon further move-

ment of the door the members engage said supports so as to support the door independently of the aforesaid rollers whereby movement of the door is frictionally resisted.

5 8. In a railway car, a plurality of brackets mounted upon the car, each provided with a roller normally supporting a horizontally movable door, members secured to the door out of the path of engagement of the rollers with the 10 door, parts mounted on the car positioned to be

engaged by said members upon movement of the door to a predetermined position so as to raise said door out of engagement with the rollers, and supports positioned so that upon further movement of the door the members drop into 80 engagement with the supports so as to support the door independently of the aforesaid rollers whereby movement of the door is frictionally resisted.
